UNITED STATES PATENT OFFICE.

RUDOLF SLABY, OF STUTTGART, GERMANY, ASSIGNOR TO DAIMLER-MOTOREN-
GESELLSCHAFT, OF UNTERTÜRKHEIM, GERMANY, A CORPORATION OF GER-
MANY.

CARBURETER.

1,160,662.

Specification of Letters Patent. Patented Nov. 16, 1915.

Application filed July 31, 1915. Serial No. 42,968.

To all whom it may concern:

Be it known that I, RUDOLF SLABY, subject of the King of Prussia, residing at 33 Dienershalde, Stuttgart, Kingdom of Württemberg, German Empire, have invented certain new and useful Improvements in Carbureters for Liquid Fuel, of which the following is a specification.

The present invention relates to carbureters for liquid fuel and its particular object is a carbureter allowing a thorough disintegration and atomization of the fuel before it enters the carbureting chamber. In order to attain this, instead of introducing the fuel into the carbureting chamber directly from the fuel nozzle or from any other aperture at the end of the fuel tube, a cap-shaped chamber is inserted between said nozzle or aperture and the carbureting chamber proper, said cap-shaped chamber communicating with the carbureting chamber through openings arranged in its wall. This arrangement causes a gradual reduction of the fuel into the gaseous state to take place, the fuel already atomized on entering the cap-shaped chamber being further atomized within said chamber by whirling and by passing from said chamber into the carbureting chamber.

Preferably the cap-shaped chamber should be arranged so as to admit part of the primary air, thus causing the fuel to be mixed with part of the air before entering the carbureting chamber. The apertures connecting the cap-shaped chamber with the carbureting chamber are preferably shaped so as to present the shortest cylindrical walls possible, and to form a keen peripheral edge. This is attained either by forming the cap-shaped chamber of thin sheet metal or else by countersinking the apertures. A plurality of cap-shaped chambers may be arranged in series.

In the drawings forming part of this specification Figures 1 and 2 are sectional views illustrating two modifications of a carbureter according to the present invention.

In the carbureter shown in Fig. 1 *a* is the float chamber, *b* is the fuel nozzle, *c* is a multi-stage resistance formed by a number of single resistances arranged in series, as shown for instance in my co-pending application, Serial No. 42,966, filed July 31, 1915, *c'* is the carbureting chamber, *d* is the cap-shaped chamber, *d'* are the apertures lead-

ing from said chamber to the carbureting chamber. The fuel escaping from the last resistance does not enter the carbureting chamber direct but passes first of all into the cap-shaped chamber *d* there to be further disintegrated by whirling and to pass through the apertures *d'* into the carbureting chamber where a fresh disintegration and atomization of the fuel will take place. The cap-shaped chamber *d*, as shown in the drawings, is preferably arranged so as to allow part of the primary air drawn in from below to enter it and to be mixed therein with the fuel.

The carbureter shown in Fig. 2 is alike in all respects to the one described above, with the only exception of the apertures *d'*, most of which are countersunk from outside, thus presenting a keen circular or other edge *d''*. The single particles of the fuel and air mixture instead of being guided by the cylindrical walls of the apertures in parallel directions are thereby forced past said keen edge and will expand immediately thereafter in the carbureting chamber.

The nozzle provided with a multi-stage resistance as shown in the drawings may be replaced by any other suitable nozzle.

I claim:

1. In a carbureter, the combination of a carbureting chamber, a fuel nozzle, a hollow member located at the free end of said nozzle and having its inner surface curved and forming a substantial continuation of the nozzle mouth whereby the fuel leaving the latter is given a whirling motion in said hollow member, the latter being provided with spaced radially disposed apertures connecting the interior of said member with said carbureting chamber.

2. In a carbureter, in combination, a fuel nozzle, a mixing chamber, a cap-shaped chamber inserted between said nozzle and said mixing chamber and a plurality of apertures in the wall of the cap-shaped chamber adapted to connect said chamber with the mixing chamber, said apertures being countersunk in the chamber wall.

3. In a carbureter, the combination of a carbureting chamber, a fuel nozzle, a hollow member located at the free end of said nozzle and having its inner surface curved and forming a substantial continuation of the nozzle mouth whereby the fuel leaving the latter is given a whirling motion in said

hollow member, the latter being provided with spaced radially disposed apertures connecting the interior of said member with said carbureting chamber, and having additional apertures in close proximity to the nozzle mouth for the admission of air to said member.

4. In a carbureter, the combination of a carbureting chamber, a fuel nozzle, a hollow member located at the free end of said nozzle and provided with apertures connecting the interior of said member with said carbureting chamber, the walls of said apertures diverging toward said chamber.
- 10 5. In a carbureter, the combination of a carbureting chamber, a fuel nozzle, a hollow member located at the free end of said nozzle and provided with apertures connecting the interior of said member with said carbureting chamber, the walls of said apertures diverging from a point between the inner

and outer surfaces of said member toward one of said surfaces.

6. In a carbureter, the combination of a carbureting chamber, a fuel nozzle, a hollow member located at the free end of said nozzle and provided with apertures connecting the interior of said member with said carbureting chamber, the diameter of each aperture being greater at one surface of said member than at the other.

7. In a carbureter, the combination of a carbureting chamber, a fuel nozzle, a hollow member located at the free end of said nozzle and provided with apertures connecting the interior of said member with said carbureting chamber, the diameter of each aperture being greater at the outer surface of said member than at the inner surface thereof.

In testimony whereof I affix my signature.
RUDOLF SLABY.
